a corporation of Delaware

Application February 25, 1946, Serial No. 650,070

10 Claims. (Cl. 316—29)

1

This invention relates to a television tube in which a part at least of an optical system is incorporated within the tube envelope, together with the electronic components thereof and it has particular reference to apparatus for and a method of aligning and assembling the components of such a tube.

In television systems, it is desirable to project upon a viewing screen an image of a television subject having suitably large dimensions to permit viewing thereof by a sizable group of observers. One means for accomplishing this object that has been employed is the formation of the television image on the fluorescent screen of a reproducing tube having a relatively small size. Such an image then is enlarged by some sort of optical system for projection upon a remotely disposed viewing screen. One optical system, which has found particular favor recently, is that employed in the so-called "Schmidt camera." This type of optical system is preferred principally for the reason that it affords a relatively wide angle of view, whereby to increase its light gathering property, and is capable of projecting the light gathered from an optical image onto a viewing screen with a minimum of distortion.

Various organizations of apparatus have been proposed to adapt the Schmidt optical system for use with a television tube, particularly a reproducing tube. Essentially, this optical system constitutes three optical imaging components: the optical surface upon which the initial image is formed, a spherical reflecting surface which is mounted in spaced concentric relation to the optical surface and facing it, and, on the other side of the optical surface and spaced therefrom, an aspherical corrector plate which optically is a refractive device. The corrector plate functions to compensate for the inherent spherical aberration of the reflecting surface.

One of the difficulties that has been encountered in adapting a reflecting optical system, such as that used in the Schmidt camera, when an attempt has been made to employ an opaque fluorescent screen, has been the non-uniform distortion produced in transmitting the light from an opaque screen through the angularly disposed walls of the tube envelope. Primarily, by reason of this difficulty, most attempts to employ a fluorescent optical surface which is opaque have been abandoned in favor of a translucent fluorescent screen formed on one end of the tube envelope. The reflecting mirror of the Schmidt system may then be located externally of the tube in such a manner that it faces the tube screen. Such an

2

arrangement, however, does not operate at maximum efficiency by reason of the loss of light due to transmission through the screen.

One expedient which has been used effectively to permit the employment of an opaque fluorescent screen in a tube adapted to function in conjunction with a reflecting optical system is the device disclosed in a copending application of Madison Cawein Serial No. 489,869 filed June 5, 1943, and entitled "Electron optical device." In this tube the spherical reflecting mirror is mounted within the tube envelope and the opposite end wall of the tube is either made optically plane and the corrector plate mounted externally 15 of the plate or this end wall is constituted by the corrector plate. In order for such a tube to function electronically, it is, of course, necessary that the electrodes be enclosed within a highly evacuated envelope. Also for such a device to function satisfactorily optically, it is essential that the 20 optical imaging components including the optical surface be located in the tube with a high degree of precision in its relationship to the reflecting member and to the corrector plate. It is exceedingly difficult, if not practically impossible, to position the optical surface of the tube with the required precision by means of jigs or the like. At 25 present, the best known system for mounting the electrode in the tube is to employ optical means, such as suitably projected light, while the tube is still in the process of formation and before it is evacuated.

It is the object of the present invention, therefore, to provide apparatus for and a method of assembling and mounting the electronic and optical imaging components of a device in which both types of components are located within a tube envelope.

In accordance with this invention, the method 40 for aligning and mounting the focal surface member in a tube envelope which also contains a reflecting member comprises the following steps: The focal surface member is inserted in the tube envelope so that it faces the reflector; a light pattern is projected onto the focal surface member 45 so that the light reflected therefrom is successively reflected by said reflector and refracted by a corrector plate and then is directed onto a viewing screen. The focal surface member and the corrector plate are then individually adjusted 50 relative to one another and to the reflector to produce the best image of the light pattern on the viewing screen. Finally, the focal surface member is rigidly sealed in its adjusted position 55 to the tube envelope.

According to a preferred form of apparatus for performing the described method of the invention, there is provided a bed which may include a pair of parallel ways, and upon which there is mounted a plurality of carriages. The optical imaging components which are to be assembled in the vacuum tube envelope are mounted respectively on these carriages. In a tube which is to embody an optical system corresponding generally to that of the Schmidt camera, the optical imaging components comprise the focal surface member, a reflecting member and a refractive corrector plate. There also is provided means for projecting an optical image onto one of the imaging components which, in the case of the Schmidt system, may be the focal surface member. A viewing screen also is provided and the apparatus additionally includes means for moving at least one of the carriages with respect to the bed and to at least one other of the carriages for the purpose of reproducing on the viewing screen a substantially exact replica of the optical image. Having adjusted the optical imaging components in this manner, facilities are provided for permanently sealing one of the imaging components in the tube in its adjusted position relative to at least one other of the components.

For a better understanding of the invention together with other and further objects thereof, reference is made to the following description, taken in connection with the accompanying drawings, and its scope will be pointed out in the appended claims.

In the accompanying drawings:

Fig. 1 is a side elevational view, partly in section, of apparatus embodying the invention;

Fig. 2 is a fragmentary view to an enlarged scale of the focal surface member showing in detail one means for supporting it for alignment within the tube envelope;

Fig. 3 is a plan view of the apparatus;

Fig. 4 is a traverse sectional view taken on the line 4—4 of Fig. 1; and

Fig. 5 is a traverse sectional view taken on the line 5—5 of Fig. 1.

Having reference now to the drawings, there will be described a preferred form of apparatus embodying the instant invention for carrying out the novel method of the invention. Generally, this apparatus resembles a lathe. It consists of a bed 11, supported by legs 12 and 13. The upper portion of the bed 11 is divided to form two parallel ways 14 and 15.

Adjacent one end of the bed 11 a head-end carriage 16 is mounted on the ways 14 and 15 and in this embodiment of the invention is securely attached thereto. There also is provided a tail-end carriage 17 similar in structure to the head-end carriage but mounted on the lathe bed in such a manner that it faces in the direction opposite to that in which the head-end carriage faces. The tail-end carriage is supported on the ways 14 and 15 so that it may be slidably moved thereover in a direction longitudinal of the lathe bed. In order to effect this movement of the tail-end carriage, there is attached to one side thereof a lead screw follower 18. This follower is provided with an internal thread for engagement with a lead screw 19. The lead screw is mounted along the front side of the lathe bed 11 and is supported at its opposite ends by bearings 21 and 22 rigidly attached to the lathe bed. At the left hand end of the lead screw as viewed in Fig. 1, there is provided a hand wheel 23 which may be turned to impart rotation to the lead screw.

There also is provided an auxiliary carriage 24, which is mounted on the ways 14 and 15 and adapted for movement longitudinally of the lathe bed. The carriage 24 is provided with a depending lead screw follower 25 best shown in Fig. 5. This follower is internally threaded for engagement with a lead screw 26 which extends along the back side of the lathe bed as shown in Fig. 3. The rear longitudinal lead screw 26 is supported adjacent to ends in bearings 27 and 28, which are rigidly attached to the side of the lathe bed. At the left hand end of the rear lead screw 26 there is attached a hand wheel 29 for imparting rotative movement to the screw. As shown best in Fig. 1, the carriage 24 is provided on its upper surface with a dovetail projection 31. This projection is adapted to engage a dovetail slide formed in the underside of a superstructure member 32 so that this member may be slidably moved transversely of the lathe bed. The superstructure 32 is provided with a depending feed screw follower 33 (Fig. 5). This follower is internally threaded and adapted to engage a feed screw 34 which extends transversely of the lathe bed and is suitably journaled in the carriage 24. There is attached to the outer end of the feed screw 34 a single crank 35 by means of which the feed screw may be rotated.

In a similar manner there is provided on the superstructure 32 a cooperating dovetail projection and slide extending perpendicularly to the top of the lathe bed. As best illustrated in Fig. 5, a support 36 is affixed to one of these dovetailing members. A feed screw follower 37 is attached to the other of these dovetailing members and is internally threaded for engagement with a feed screw 38. This feed screw is mounted in the superstructure 32 perpendicularly to the lathe bed and has attached to its extending end a double crank 39 by means of which the feed screw may be rotated.

The construction of the head-end carriage 16 and the tail-end carriage 17 is generally similar. Fig. 4 shows a face view of the tail-end carriage. The upright portion of the carriage which extends perpendicularly to the bed 11 is circular and is provided with a plurality of thumb screws, such as 41, 42 and 43 spaced approximately at 120 degree angles relative to one another around the carriage. The central portion of the upright carriage section is provided with a circular opening 44 into which is set an annular split sleeve 45. This sleeve may be made of wood or some other equivalent material. The inside of the sleeve 45 is provided with an annular groove 46, best illustrated in Fig. 1. The sleeve 45 preferably is made somewhat smaller in diameter than the circular opening 44. The thumb screws 41, 42 and 43 are threaded through a convenient portion of the carriage so that the ends thereof engage the outer peripheral edge of the sleeve 45.

The head-end carriage 16 is provided with a collar 47 which extends at right angles from the face of the carriage. Inside of this collar is mounted a split sleeve 48 similar in material to the tail-end sleeve 46. Also the carriage is provided with a plurality of thumb screws such as the screw 49. These thumb screws are spaced around the vertical section of the carriage in a substantially similar manner to the corresponding thumb screws of the tail-end carriage 17. The ends of the head-end thumb screws, such as 49, are adapted to engage the outer peripheral surface of the sleeve 48, which preferably is made

somewhat smaller in diameter than the inside diameter of the collar 47.

The auxiliary carriage support 36 supports a rod 50 (see Figs. 3 and 5) which extends perpendicularly from the support across the bed 11 of the apparatus. There also is affixed to the rod 50, either rigidly or adjustably as by a clamp coupling 51, a second rod 52 which is an elongated member and extends longitudinally of the bed 11 in the direction of the carriage 17. The outer end of the elongated rod 52 is provided with a hole 53 (see Fig. 2) which is drilled into the end of the rod for a purpose to be described.

In using the described apparatus for the purpose of aligning the focal surface member in a tube of the character described, the tube blank is mounted in the head-end carriage 16. In one form of the tube, it comprises a main body portion 54 which at one end is formed into a plane optical window 55 disposed substantially at right angles to the long axis of the tube. On the inside of the wall of the main body portion of the tube opposite to the window 55 there is provided a concave reflector 56. As illustrated, this end wall of the tube is spherically shaped and the reflector 56 is mounted directly thereon. It, however, is contemplated that other forms of tubes may be employed within the scope of this invention wherein, for example, the reflector 56 is separately supported with the body portion 54 of the tube in spaced relation to the end walls thereof. The reflector 56 has a central opening formed therein which is in register with a relatively long tubulation 57 extending from the main tube body 54. This tubulation is for the purpose of housing suitable electronic apparatus for cooperating with the focal surface member when the tube is completed. At this stage of the construction of the tube, the outer end of the tubulation 57 is open to the atmosphere. A relatively short stem 58 is formed so that it extends outwardly along the central axis of the tube from the window 55.

The tube envelope as described is inserted in the split sleeve 48 and the plurality of thumb screws such as the screw 49 are tightened to deform the sleeve sufficiently to securely grip the tube body 54. In this manner, the tube envelope is rigidly secured to the head-end carriage 16 substantially in the manner illustrated in Fig. 1.

The next step in the formation of the tube is to insert the focal surface member. The general character of this member is illustrated best in Fig. 2 of the drawings. The focal surface member 59 has a generally convex spherical configuration. It is mechanically and electrically mounted on the end of a lead 61 which is disposed substantially at the center of the electrode. The lead 61 is sealed into one end of a small glass tubular member 62 which at the outer end thereof is provided with a flared portion 63. The lead 61 extends through the member 62 for some little distance beyond the flared end thereof.

The elongated rod 52 is detached from the supporting rod 50 at the coupling 51 so that it may be attached temporarily to the focal surface supporting structure. As shown in Fig. 2, the outer end of the rod 52 is of slightly smaller external diameter than the internal diameter of the tubular member 62. First, there is wrapped around the end of the rod 52, a layer of material 64 such as asbestos for example. The wrapping 64 then is moistened and the end of the rod 52 inserted into the tubular member 62 in somewhat the position shown.

The rod 52 with the focal surface member 59

attached thereto in the manner described, then is ready for insertion in the tube. Before this step is taken, however, the corrector plate for the optical system is mounted in the tail-end carriage 17. The corrector plate 65 is inserted in the split sleeve 45 in such a manner that the peripheral edge thereof lies within the annular groove 46. The corrector plate is secured in the mounted sleeve by tightening the thumb screws 41, 42 and 43.

The tail-end carriage 17 then is moved longitudinally of the bed 11 to substantially the position shown in Fig. 1. The rod 52 then is inserted through the tubulation 57, out through the stem 58 and through a centrally disposed aperture 66 formed in the corrector plate 65 and is then attached to the supporting rod 50 by means of the coupling 51. At this stage, the tube containing the reflector 56, the focal surface member 59 and the corrector plate 65 are located approximately in the desired relative positions.

A light projector 67 then is mounted by suitable means (not shown) to project a light pattern through the tubulation 57, onto the focal surface member 59. Adjacent the other end of the apparatus, there is mounted a viewing screen 68 in alignment with the longitudinal axis of the optical system. An optical image is projected onto the focal surface member 59 from the projector 67 and may be of any desired character. For example, it may be a conventional test pattern used generally in television systems. The light reflected from the focal surface member 59 representative of the optical image is directed onto the spherical surface of the reflector 56 and then is transmitted through the refractive corrector plate 65 for ultimate projection onto the viewing screen 68. The manner in which the optical system functions may be determined by an observation reproduced by the optical image on the screen 68. The apparatus then is adjusted in a manner to be described to project the image onto the screen 68 to produce the best possible result.

In order for the optical system to function in the manner desired, it is necessary that the focal surface member 59 be located within the tube body 54 so that it is concentric with the surface of the reflector 56. The corrector plate 65 must also be located at the proper distance from the reflector 56. It also must be positioned to be in substantial coaxial alignment with the focal surface member 59 and the reflector. The spacing between the focal surface member, the reflector, the corrector plate and the screen 68 must bear a definite relationship to the magnification desired. In making the necessary adjustment to achieve this spacing, the head-end carriage 16 is permanently located on the bed 11. Consequently, the reflector 56 is fixed in position. Also, in accordance with the desired focal distance of the system, the screen 68 is located permanently at a predetermined distance from the reflector 56. The spacing of the corrector plate 65 is adjusted by moving the tail-end carriage 17 under the control of the lead screw 19 effected by suitable manipulation of the hand wheel 23. The spacing of the focal surface member 59 is similarly adjusted by moving the auxiliary carriage 24 under the control of the lead screw 26 effected by suitable turning of the hand wheel 29.

The axial alignment of the corrector plate is adjusted by means of the thumb screws 41, 42 and 43. By a suitable manipulation of the screws,

the corrector plate may be moved both transversely of and perpendicularly to the bed 11. The axial alignment of the focal surface 59 is effected by suitable manipulation of the superstructure 32 and the mounting plate 36 of the auxiliary carriage 24. Transverse movement of the focal surface relative to the bed 11 is effected by a manipulation of the single crank 35 whereby the superstructure 32 is moved across the bed. Vertical movement of the focal surface member is effected by the proper manipulation of the double crank 39 whereby the mounting plate 36 is moved perpendicularly to the bed.

All of these adjustments are made while viewing the optical image projected onto the screen 68. When the best possible reproduction of the light pattern has been produced on the screen, it indicates that the optical system has been properly aligned. Heat is then applied to the protruding stem 58 of the tube by means such as a plurality of flames 69, for example, whereby to fuse the flared portion 63 of the stem 62 thereto. In this manner there may be made an airtight joint between the tubular member 62 and the stem 58. The rod 52, then may be detached from the tubular member 62 by a combined twisting and pulling action. The focal surface member 59 as a result will be rigidly mounted in the tube at the proper distance from the reflector 56 and in coaxial alignment therewith. The tube then may be demounted from the apparatus for the insertion of the electronic structure in the tubulation 57 thereof and for the sensitization of the convex surface of the focal surface member, after which the envelope may be evacuated and sealed in the usual manner.

The foregoing description of a preferred form of the invention has considered only the attachment of the focal surface member 59 to the tube envelope. It may be desirable in the fabrication of tubes of this character to make the corrector plate 65 a part of the tube. In such a case, it is possible to dispense with the plane window 55 and to substitute for it the corrector plate located, of course, at the proper distance from the reflector 56. It is contemplated to be within the scope of the present invention to employ similar apparatus and substantially the same method for the production of a tube of this character. After the proper alignment of the components of the system, it is merely necessary to fuse the peripheral edge of the corrector plate, such as the plate 65, to the circumferential walls of the tube body 54 in addition to fusing the equivalent of the tubular member 62 to the tube envelope. In such a case, it may be preferable to use an apparatus such as that desired set up vertically instead of horizontally as herein illustrated and described.

It will be obvious to those skilled in the art that the described apparatus may also be employed for assembling a vacuum tube having a plurality of optical imaging components where the optical system is something different than the system of the Schmidt camera. For example, the optical system may consist only of a focal surface member and either a reflector or a refraction device such as a lens. Each of two such components may be mounted respectively on carriages supported by a bed. One or both carriages may be moved relative to the other in order properly to align the imaging components. In such a case, when the proper adjustment has been effected whereby a good reproduction of the optical image is projected onto the viewing screen, the two components may be securely fastened relative to one

another such as by sealing both of them to a tube envelope.

Throughout the foregoing description and in the appended claims, the term "focal surface member" is used. The present specification consists specifically of a projection reproducing tube. This treatment of the invention, however, is intended to be illustrative only. It obviously is within the scope of this invention to employ the same apparatus and method for the production of a television tube of the image analyzing type, such as is used in conjunction with transmitting apparatus. The only difference between the two types of tubes as far as present considerations are concerned is in the character of the focal surface member and the electronic apparatus used in conjunction therewith. For a reproducing tube, the focal surface member will have formed thereon a fluorescent screen for bombardment by a stream of electrons from an electron gun mounted in the tubulation 57 in order to produce an optical image for projection onto the viewing screen. In the case of an image analyzing tube, the focal surface member will be conditioned to produce photo-electric effects in response to the projection thereon of an optical image which is to be converted in a train of signals representative thereof by suitably scanning the resultant electron image by conventional means located in the tubulation 57.

While there has been described what, at present, is considered the preferred embodiment of the invention, it will be obvious to those skilled in the art that various changes and modifications may be made therein without departing from the invention, and it, therefore, is aimed in the appended claims to cover all such changes and modifications as fall within the true spirit and scope of the invention.

40. What is claimed is:

1. In apparatus for assembling a vacuum tube having a plurality of optical imaging components incorporated therein, a bed, a plurality of carriages mounted on said bed for supporting respectively said imaging components, means for projecting an optical image onto one of said components, a viewing screen, means for moving one of said carriages with respect to said bed and to another of said carriages, whereby to effect the reproduction on said viewing screen of a substantially exact replica of said optical image, and means for permanently sealing one of said imaging components in said tube in its adjusted position relative to others of said components.

45. 2. In apparatus for assembling a vacuum tube having a plurality of optical imaging components incorporated therein, a bed, a fixed carriage mounted on said bed for supporting one of said imaging components, a movable carriage mounted on said bed for supporting another of said imaging components, means for projecting an optical image onto one of said components, a viewing screen, means for moving said movable carriage on said bed, whereby to effect the reproduction on said viewing screen of a substantially exact replica of said optical image, and means for permanently sealing one of said imaging components in said tube in its adjusted position relative to the other of said components.

50. 3. Apparatus for assembling a vacuum tube having a plurality of optical imaging components incorporated therein comprising, a bed having a pair of parallel ways, a fixed carriage mounted on said bed for supporting one of said imaging components, a plurality of movable carriages mount-

ed on said bed for supporting respectively others of said imaging components, means for projecting an optical image onto one of said components, a viewing screen, means for independently moving said movable carriages with respect to said bed and to one another, whereby to effect the reproduction on said viewing screen of a substantially exact replica of said optical image, and means for permanently sealing one of said imaging components in said tube in its adjusted position relative to others of said components.

4. Apparatus for locating a focal surface member in the envelope of a television tube having incorporated therein a spherical reflector comprising, a lathe bed having a pair of parallel ways, a fixed carriage mounted on said ways for rigidly supporting the tube envelope, a movable carriage mounted on said ways in an opposing position to said fixed carriage, means for moving said movable carriage longitudinally on said ways, a corrector plate adjustably mounted on said movable carriage adjacent said envelope in such manner that said corrector plate may be moved both transversely and perpendicularly to said lathe bed ways, an auxiliary carriage mounted on said lathe bed ways and adapted for movement longitudinally of said ways, a superstructure mounted on said auxiliary carriage and adapted for movement on said auxiliary carriage transversely of said lathe bed ways, a sliding support mounted on said superstructure and adapted for movement perpendicularly to said lathe bed ways, and a support attached to said sliding member and extending into said envelope for supporting said focal surface member within said tube envelope.

5. Apparatus for locating a focal surface member in the envelope of a television tube having incorporated therein a spherical reflector comprising, a lathe bed having a pair of parallel ways, a fixed carriage mounted on said ways, means for rigidly mounting the tube envelope on said fixed carriage, a movable carriage mounted on said ways in an opposing position to said fixed carriage, means for moving said movable carriage longitudinally on said ways, means for adjustably mounting a corrector plate on said movable carriage adjacent said envelope in such a manner that said corrector plate may be moved both transversely and perpendicularly to said lathe bed ways, an auxiliary carriage mounted on said lathe bed ways and adapted for movement longitudinally of said ways, a superstructure mounted on said auxiliary carriage and adapted for movement on said auxiliary carriage transversely of said lathe bed ways, a sliding support mounted on said superstructure and adapted for movement perpendicularly to said lathe bed ways, and a supporting member attached to said sliding member and extending into said envelope for adjustably supporting said focal surface member within said tube envelope.

6. Apparatus for locating a focal surface member in the envelope of a television tube having incorporated therein a spherical reflector comprising, a lathe bed having a pair of parallel ways, a head-end carriage mounted on said ways, a first supporting structure attached to said head-end carriage for rigidly mounting the tube envelope on said head-end carriage, a tail-end carriage mounted on said ways in an opposing position to said head-end carriage, means for moving said tail-end carriage longitudinally on said ways, a second supporting structure attached to said tail-end carriage for mounting a corrector plate adjacent said envelope opposite to said reflector,

means embodied in said tail-end carriage for adjustably holding said corrector plate in said second supporting structure in such a manner that said corrector plate may be moved both transversely and perpendicularly to said lathe bed ways, an auxiliary carriage mounted on said lathe bed ways, means for moving said auxiliary carriage longitudinally of said ways, a superstructure mounted on said auxiliary carriage, means for moving said superstructure on said auxiliary carriage transversely of said lathe bed ways, a sliding support mounted on said superstructure, means for moving said sliding support perpendicularly to said lathe bed ways, and a stiff supporting member attached to said sliding member and extending longitudinally of said lathe bed ways to the interior of said envelope, said supporting member being provided with facilities at its extended end for supporting said focal surface member.

7. Apparatus for locating a focal surface member in the envelope of a television tube having incorporated therein a spherical reflector comprising, a lathe bed having a pair of parallel ways, a head-end carriage mounted on said ways and having a portion extending substantially perpendicularly upward from said ways, a first supporting structure attached to said head-end carriage for rigidly mounting the tube envelope in such position that an open tubulation formed in the tube wall opposite to said reflector extends outwardly from said head-end carriage in a direction substantially parallel to said ways, a tail-end carriage mounted on said ways in an opposing position to said head-end carriage, means including a first lead screw for moving said tail-end carriage longitudinally on said ways, a second supporting structure attached to said tail-end carriage for mounting an aspherical refractive corrector plate adjacent said envelope tubulation, said corrector plate having an aperture mounted substantially in alignment with said tubulation, means including a plurality of thumb screws threaded into said tail-end carriage for adjustably holding said corrector plate in said second supporting structure in such a manner that said corrector plate may, by manipulation of said thumb screws, be moved both transversely and perpendicularly to said lathe bed ways, an auxiliary carriage mounted on said lathe bed ways, means including a second lead screw for moving said auxiliary carriage longitudinally of said ways, a superstructure mounted on said auxiliary carriage, means including a third lead screw for moving said superstructure on said auxiliary carriage transversely of said lathe bed ways, a sliding support mounted on said superstructure and adapted for movement perpendicularly to said lathe bed ways, a fourth lead screw for effecting said perpendicular movement of said sliding member, and a rod attached to said sliding member and extending longitudinally of said lathe bed ways through the aperture in said corrector plate and the open tubulation of said envelope, said rod being provided with facilities at its extended end for supporting said focal surface member within said tube envelope.

8. Apparatus for locating a focal surface member in the envelope of a television tube having incorporated therein a spherical reflector comprising, a lathe bed having a pair of parallel ways, a head-end carriage mounted in fixed position on said ways and having a portion extending substantially perpendicularly upward from said ways, a first clamping structure attached to the

upright portion of said head-on carriage for rigidly mounting the tube envelope in such position that an open tubulation formed in the tube wall opposite to said reflector extends outwardly from said head-end carriage in a direction substantially parallel to said ways, a tail-end carriage mounted on said ways in an opposing position to said head-end carriage, means including a first lead screw for moving said tail-end carriage longitudinally on said ways, a second clamping structure attached to said tail-end carriage for mounting an aspherical refractive corrector plate adjacent said envelope tubulation, said corrector plate having an aperture mounted substantially in alignment with said tubulation, a plurality of thumb screws threaded into said tail-end carriage and spaced around the periphery of said second clamping structure for adjustably holding said corrector plate in said second clamping structure in such a manner that said corrector plate may, by manipulation of said thumb screws, be moved both transversely and perpendicularly to said lathe bed ways, an auxiliary carriage mounted on said lathe bed ways, means including a second lead screw for moving said auxiliary carriage longitudinally of said ways, a superstructure mounted on said auxiliary carriage, means including a third lead screw for moving said superstructure on said auxiliary carriage transversely of said lathe bed ways, a sliding support mounted on said superstructure and adapted for movement perpendicularly to said lathe bed ways, a fourth lead screw for effecting said perpendicular movement of said sliding member, and an elongated rod attached to said sliding member and extending longitudinally of said lathe bed ways through the aperture in said corrector plate and the open tubulation of said envelope, said elongated rod being provided with facilities at its extended end for supporting said focal surface member within said tube envelope.

9. The method of mounting a focal surface

- member in the envelope of a television tube together with a spherical reflector comprising the steps of, rigidly supporting said reflector in the tube envelope, adjustably supporting said focal surface member within said tube envelope, adjustably supporting a refractive corrector plate external of said tube envelope, projecting a light pattern on said focal surface member, individually adjusting the positions of said focal surface member and said corrector plate to produce a substantially undistorted image of said light pattern in a predetermined focal plane, and sealing said focal surface member to said tube envelope in its adjusted position.
10. The method of mounting a focal surface member in the envelope of a television tube having incorporated therein an apertured spherical reflector comprising the steps of, rigidly supporting the tube envelope and the incorporated reflector, adjustably supporting an apertured refractive corrector plate external of said tube envelope, adjustably supporting said focal surface member within said tube envelope through the aperture in said corrector plate, projecting a light pattern on said focal surface member through the aperture in said reflector, individually adjusting the positions of said focal surface member and said corrector plate to produce a substantially undistorted image of said light pattern in a predetermined focal plane, and sealing said focal surface member to said tube envelope in its adjusted position.

CHRISTIAN C. LARSON.
